METHOD OF DEHYDRATING AQUEOUS
SOLUTIONS OF FORMIC ACID

Henri Martin Guinot, Versailles, France, assignor
to Les Usines De Melle (Societe Anonyme),
Saint-Leger-les-Melle, France, a company of
France

Application June 15, 1945, Serial No. 599,606
In France April 4, 1941

Section 1, Public Law 690, August 8, 1946
Patent expires April 4, 1961

10 Claims. (Cl. 202—42)

1
It is known that azeotropic dehydration of formic acid solutions causes particular difficulties by reason of the fact that formic acid forms with water an azeotrope having a maximum boiling point; the azeotrope boils at 107.1° C. and contains 77 parts of acid and 23 parts of water. Hence, when an aqueous solution of formic acid having an acid content above 77 per cent is distilled, formic acid exhibits a tendency to rise to the top of the column, thereby practically preventing the insoluble liquid employed as a water entrainer to perform its function.

In U. S. Patent No. 1,896,100 dated February 7, 1933, there has been described a method capable of doing away with the difficulty; according to said method, azeotropic distillation is carried out in the presence of a diluent having a high boiling point which may be the water entrainer itself and is adapted to hold the acid in the bottom part of the column. Dehydration is performed in one step in the distilling column; a second column is used merely to separate anhydrous acid from diluent.

It is a primary object of my invention to provide a novel, simpler and more efficient manner of dehydrating aqueous solutions of formic acid.

According to this invention, aqueous formic acid to which no diluent has been added and which may have been brought, if desired, by distillation to the concentration corresponding to azeotrope, is introduced into the middle part of a column that has been charged once for all with a suitable amount of a water entrainer, said amount being so selected as to leave in the lower part of the column a number of non-occupied plates preventing the entrainer from reaching the lowermost portion of the column.

The operation of the column is so controlled that water is not thoroughly removed and formic acid flowing out from the bottom of the column still contains from 5 to 15 per cent of water.

The entrainer forms with water in the aqueous acid fed to the column a binary mixture having a minimum boiling point which is withdrawn from the top of the column and is caused to settle into two layers. The upper layer containing water entrainer is returned as a whole into the column. As to the lower layer consisting of water substantially free from formic acid, it is split into two portions; one of them corresponding to the necessary amount for securing desired con-

centration is withdrawn from the apparatus and discarded after recovery through distillation of the slight amount of water entrainer dissolved therein; the other fraction is returned to the top of the column together with the upper layer. The water return which is a characteristic feature of this invention has a twofold purpose:

On the one hand, to shove down to the foot of the column by washing effect, any formic acid which would tend to rise to the top;

On the other hand, to keep within the column a sufficiently large amount of water for maintaining the water entrainer engaged in an azeotropic mixture in that part of the column where it is designed to operate and preventing the same to sink to the foot as it would have a tendency to do when its boiling point differs but little from that of formic acid or is higher.

Owing to the above feature, an aqueous layer free from formic acid is obtained in the decanter while formic acid at about 85 to 95 per cent is withdrawn substantially free from water entrainer from the foot of the column.

The partly dehydrated acid is then subjected to simple distillation in a second column from the top of which part of formic acid is obtained in perfectly anhydrous condition while the remainder is recovered from the foot as a 77 per cent azeotrope which is returned to the first column.

As a water entrainer preference will be given to formic esters, particularly butyl formate (B. P. 106.9° C.), isobutyl formate (B. P. 97.9° C.), amyl formate (B. P. 130.4° C.) and isoamyl formate (B. P. 123° C.). Nevertheless, it is possible without departing from the spirit of this invention to use other entrainers, for instance ethers such as dibutyl ether, ketones such as methylpropylketone, and so on.

Where acid to be dehydrated has a concentration substantially above 77 per cent, it may be fed directly to the second column, the first column being still used for treating 77 per cent acid obtained as a tail in the second column.

Bearing in mind that acid concentration on the various plates regularly increases from the acid ingress point in the first column down to the foot and from the acid ingress point in the second column up to the top thereof, it will readily be understood that the method in accordance with this invention enables of treating acid of any concentration; suffice it to provide for each column a

plurality of acid supply points and to introduce the acid to be treated at a point where the concentration of acid boiling on the opposite plate corresponds to that of the supply liquid.

It is still within the spirit of this invention to bring about minor modifications in the above described method; for instance, instead of withdrawing anhydrous formic acid from the very top of the second column, it may be advantageous to withdraw it laterally in so-called "pasteurized" form so as to reserve in the uppermost portion of the column some plates whereon come slight amounts of water entrainer which in spite of the precautions taken might have reached the foot of the first column.

The said entrainer admixed with a large proportion of formic acid and possibly some amounts of water is withdrawn at the required speed and returned to the first column wherein its components classify themselves.

The following examples with reference to the diagrammatic appended drawing will better show the character of this invention.

Example 1.—Let us consider a 77 per cent solution of formic acid.

Column 3 being charged once for all with a suitable amount of butyl formate (hatched portion), formic acid to be dehydrated is transferred from tank 1 into the middle portion of the column through pipes 2, 2a. Owing to butyl formate being present on column plates, azeotrope water-butyl formate boiling at 85° C. is readily formed. It is condensed in condenser 4, then forwarded to decanter or settling separator 5 wherein it settles into two layers; the upper layer is returned as a whole into the upper portion of column 3 through pipe 6; as to the lower layer, composed of water free from acid but containing a small amount of dissolved formate, it is partly withdrawn at the required speed through pipe 7 while the remainder is returned to the upper portion of column 3 through pipe 8.

In the foot portion of column 3 wherein a temperature of 103.5° C. is maintained, formic acid at a concentration of about 90 per cent gathers practically free from butyl formate; it flows by gravity into column 10 through pipe 11. From the top portion of the latter, anhydrous formic acid is laterally withdrawn through pipe 12 while 77 per cent azeotrope boiling at 107° C. and behaving as a tail is shoved down to the foot wherefrom it flows into tank 13. Pump 14 forwards it from tank 13 into tank 1 through pipe 15.

Controllable means 16 are provided on the return pipe from the condenser to column 10 for withdrawing any slight amounts of butyl formate which might have entered column 10. Said formate, admixed with formic acid and possibly water, is returned to column 3 through pipe 17 opposite acid ingress points.

Assuming that original acid has a concentration slightly different from 77 per cent, it will be fed to column 3 either through pipe 2b or through pipe 2c according as said concentration is above or below 77 per cent.

Example 2.—Let us consider 95 per cent formic acid to be dehydrated.

Said acid is introduced directly into column 10 through pipes 18, 18b. Dibutyl ether has been charged in column 3 as a water entrainer. The operation of the apparatus is the same as described in Example 1.

Assuming that 88, 90 or 97 per cent formic acids are to be dehydrated, pipes 18d, 18c or 18a re-

spectively will be used for acid supply to the column.

Finally, it is within the spirit of this invention to carry out the whole method or steps thereof at a pressure other than atmospheric.

What I claim is:

1. A continuous process for dehydrating aqueous formic acid having an acid content not substantially less than 77 per cent, which comprises continuously introducing aqueous formic acid to be dehydrated into a cycle for formic acid including, spaced apart therein and placed in intercommunication thereby, an azeotropic distillation column and a simple distillation column, the azeotropic distillation column containing a predetermined amount of a water entrainer which is adapted to form an azeotrope with water but no azeotrope with formic acid and is stable in the presence of formic acid, said azeotropic distillation column being operated to remove part of the water from the aqueous formic acid, thereby leaving an aqueous formic acid having an acid content considerably above 77 per cent to be passed to the simple distillation column, while the latter is operated to separate anhydrous formic acid which rises to the top thereof, from residual 77 per cent acid which returns through said cycle to said azeotropic distillation column; continuously discarding said water; and continuously withdrawing anhydrous formic acid from the cycle out of the top portion of the simple distillation column.

2. A continuous process for dehydrating aqueous formic acid having an acid content not substantially less than 77 per cent, which comprises continuously introducing the aqueous acid to be dehydrated into a primary cycle for formic acid including, spaced apart therein and placed in intercommunication thereby, the lower portion of an azeotropic distillation column and the lower portion of a simple distillation column, the azeotropic distillation column containing a predetermined amount of a water entrainer which is adapted to form an azeotrope with water but no azeotrope with formic acid and is stable in the presence of formic acid, said azeotropic distillation column being operated to produce entrainer-water azeotrope vapours as a head product and leave as a bottom product, an aqueous formic acid having an acid content considerably above 77 per cent which is introduced through said primary cycle into the simple distillation column above the bottom thereof, while said simple distillation column is operated to separate anhydrous formic acid, which rises to the top thereof, from residual 77 per cent formic acid which is returned from the bottom of said simple distillation column through said primary cycle to and above the bottom of said azeotropic distillation column; continuously withdrawing said azeotrope vapours from the top of said azeotropic distillation column; condensing said vapours in a condensing zone to obtain an aqueous condensate; causing said condensate to settle into two layers comprising an aqueous layer, in a decanting zone; discarding part of said aqueous layer, while refluxing the remainder of said condensate to said top portion of said azeotropic column so that said water entrainer is continuously cycled through

70 a secondary cycle including in sequence said top portion of said azeotropic distillation column; said condensing zone and said decanting zone; and continuously withdrawing anhydrous formic acid from said primary cycle, out of the top portion of 75 said simple distillation column.

3. The process of claim 2, the aqueous formic acid to be dehydrated being introduced into the primary cycle at a point thereof where a formic acid concentration substantially equal to the concentration of said aqueous formic acid prevails.

4. The process of claim 2, the predetermined amount of water entrainer in the azeotropic distillation column and the amount of water removed from the decanting zone being such that the total amount of water entrainer in the 10 azeotropic distillation column is engaged as an azeotrope with water in said column.

5. The process of claim 2, the predetermined amount of water entrainer in the azeotropic distillation column being such that the water entrainer in said column is wholly confined above said point of egress of the aqueous formic acid.

6. The process of claim 2, anhydrous formic acid being withdrawn from the top portion of the simple distillation column at a point below the uppermost point of said column.

7. The process of claim 2, anhydrous formic acid being withdrawn from the top portion of the simple distillation column at a point below the uppermost point of said column, the process further comprising the step of withdrawing vapours from said simple distillation column at a point above the withdrawal point for anhydrous formic acid; condensing said vapours into a liquid, returning part of said liquid into the top portion of said simple distillation column and the remainder into the azeotropic distillation column.

8. The process of claim 2, the water entrainer being selected from the group consisting of aliphatic formic esters having 5 and 6 carbon atoms, dibutyl ether and methyl propylketone.

9. A continuous process for the production of anhydrous formic acid, which comprises cycling aqueous formic acid successively through the lower portion of an azeotropic distillation column and the lower portion of a simple distillation column, the azeotropic distillation column containing a predetermined amount of a water entrainer which is adapted to form an azeotrope with water but no azeotrope with formic acid and is stable in the presence of formic acid, said azeotropic distillation column being operated to produce entrainer-water azeotrope vapours as a head product and to leave as a bottom product an aqueous formic acid having an acid content considerably above 77 per cent which is introduced through said cycle into the simple distillation column above the bottom thereof, while said simple distillation column is operated to separate anhydrous formic acid which rises to the top thereof, from residual 77 per cent formic acid which is returned from the bottom of said simple distillation column through said cycle to and above the bottom of said azeotropic distillation column; withdrawing said azeotrope vapours from the top of said azeotropic distillation column; condensing said vapours to obtain an aqueous

condensate; causing said condensate to settle into two layers comprising an aqueous layer; discarding a portion of said aqueous layer; refluxing the remainder of said condensate to the upper portion of said azeotropic distillation column; withdrawing anhydrous formic acid from the top portion of the simple distillation column; and feeding aqueous formic acid having a strength above 77% to said simple distillation column at a level where formic acid in said column has substantially the same strength as the aqueous formic acid thus fed.

10. A continuous process for the production of anhydrous formic acid, which comprises cycling aqueous formic acid successively through the lower portion of an azeotropic distillation column and the lower portion of a simple distillation column, the azeotropic distillation column containing a predetermined amount of a water entrainer which is adapted to form an azeotrope with water but no azeotrope with formic acid and is stable in the presence of formic acid, said azeotropic distillation column being operated to produce entrainer-water azeotrope vapours as a head product and to leave as a bottom product an aqueous formic acid having an acid content considerably above 77 per cent which is introduced through said cycle into the simple distillation column above the bottom thereof, while said simple distillation column is operated to separate anhydrous formic acid which rises to the top thereof, from residual 77 per cent formic acid which is returned from the bottom of said simple distillation column through said cycle to and above the bottom of said azeotropic distillation column; withdrawing said azeotrope vapours from the top of said azeotropic distillation column; condensing said vapours to obtain an aqueous condensate; causing said condensate to settle into two layers comprising an aqueous layer; discarding a portion of said aqueous layer; refluxing the remainder of said condensate to the upper portion of said azeotropic distillation column; withdrawing anhydrous formic acid from the top portion of the simple distillation column; and feeding aqueous formic acid having a strength of about 77% to said azeotropic distillation column at a level where aqueous formic acid therein has substantially the same strength as the acid thus fed.
